G. F. GRUBE & J. V. MEYERING.
TRUNK LOCKING MECHANISM.
APPLICATION FILED OCT. 25, 1915.

1,172,791.

Patented Feb. 22, 1916.

FIG. 1.

UNITED STATES PATENT OFFICE.

GEORGE F. GRUBE, OF EVANSTON, AND JULIUS V. MEYERING, OF CHICAGO, ILLINOIS.

TRUNK-LOCKING MECHANISM.

1,172,791.

Specification of Letters Patent. Patented Feb. 22, 1916.

Application filed October 25, 1915. Serial No. 57,664.

To all whom it may concern:

Be it known that we, GEORGE F. GRUBE and JULIUS V. MEYERING, citizens of the United States, the former a resident of Evanston, Cook county, Illinois, and the latter of Chicago, Cook county, Illinois, have invented certain new and useful Improvements in Trunk-Locking Mechanism, of which the following is declared to be a full, 10 clear, and exact description.

This invention relates to locking mechanism for trunks, suitcases, satchels and other portable containers, for use in transporting baggage and other articles, and its 15 principal object is to provide locking mechanism of this class, of novel and improved construction.

Another object is to provide locking mechanism of this class, with improved means for 20 locking together the two sections of a trunk or other object, at a plurality of places on the inside thereof, said means being operated by a movable locking member, located on the 25 outside of the trunk or other object, thereby dispensing with catches or locks at various places on the outside of the trunk, which catches must be operated individually in fastening the two halves of the trunk together.

Other objects are to simplify locking 30 mechanism of this class, and to strengthen and otherwise increase the efficiency thereof, and with all of said objects and advantages in view this invention consists in the several novel features of construction, arrangement and combination of parts hereinafter described and claimed.

The invention is clearly illustrated in the accompanying drawing, in which:—

Figure 1, is a vertical section through a 40 trunk, showing in side elevation, a trunk locking mechanism embodying a simple form of the present invention, in locked position, applied thereto; Fig. 2, is a side view of the same parts, with portions of the trunk body broken away, the locking mechanism being shown in unlocked position and the two trunk sections partly opened; Fig. 3, is a side elevation of a fragment of the trunk, showing the outer locking members; Fig. 4, is a detail, horizontal section taken on line 4—4, Fig. 1; Fig. 5, is a detail, horizontal section taken on line 5—5, Fig. 1; Fig. 6, is a perspective view of a lock bar shifting member and Fig. 7, is a side elevation of a slightly modified form of lock bar shifting means.

Referring first to Figs. 1, to 6, inclusive of said drawing, which illustrate the preferred embodiment of the invention, 10, 11, indicate the two sections or members of a trunk, hinged together as usual, and capable of containing many of the common and well-known compartment devices and other apparatus for receiving clothes and other baggage. Near one end of the meeting edges 12, 13, of the two sections is the outer locking mechanism 14, which may comprise the usual hasp member 15, mounted on one section and socket member 16, mounted on the other section and adapted for locking engagement with said hasp member in accordance with the common and well-known practice. In the form shown, the hasp member 15, has a hinge joint at 17, whereby the hinged part may swing toward and away from the socket member in locking or unlocking the trunk, and said hasp member 15, is pivotally mounted on the trunk section 11, on a horizontal pivot, whereby it may be swung upward from the 80 position shown in full lines in Fig. 3, to that shown in dotted lines and vice versa, for the purpose of actuating the internal locking mechanism. Conveniently the hasp member has an inwardly extending pin or bolt 18, rigidly secured thereto and projecting through an opening in the trunk section and turning freely therein. The inner end of said pin or bolt 18, is squared, and rigidly secured to said squared end is 90 a segmental rack 19, the teeth 24, of which mesh with teeth 20, on a lock bar 21, which is slidably mounted on the inside of the trunk section 11. In the form illustrated, said teeth 20, are formed in said lock bar 95 21, near one end thereof, and the segmental rack has two flat sides 22, 23, arranged at right angles to each other and adapted to strike against the adjacent toothed edge of the lock bar, to thereby limit the movement 100 of said bar, and hasp member in either direction, the parts being so proportioned that movement of the hasp member through an arc of 90 degrees shifts the lock bar 21 through the necessary distance to lock or unlock the internal locking mechanism. The lock bar is guided to move in a lengthwise direction by straps 25, secured to the trunk section 11 and overhanging the bar. On the adjacent side opposite trunk section 110 10, are fastened a plurality of stationary or fixedly secured internal lock members 26,

which project across the meeting edges of the two trunk sections and are arranged for locking engagement with the sliding lock bar 21. In the form shown said internal lock members 26, are formed with notches 27, in their upper edges, near their outer ends, adapted to receive lock bolts or lugs 28, carried by, and preferably formed integral with the sliding lock bar 21. Conveniently the notches 27, have inclined edges 29 inclined upwardly and outwardly, and the lock bolts or lugs, 28, have similarly inclined edges 30, adapted for engagement with and coacting with said inclined edges 15 of the notches 27, to force the two trunk sections together. At the upper ends of the inclined edge portions 29, of the notches 27, are upstanding lugs 31, which are adapted to engage with straight edges on the rear 20 sides of the lock bolts or lugs 28, whereby when the parts are in locked position said straight edges engage each other and positively prevent relative movement between the two trunk sections. When the lock bolts 25 or lugs 28, are formed integral with the lock bar 21, notches 32, may be formed in said lock bar behind and below the lock bolts or lugs 28, for the reception of the notched ends of the internal lock members 30, and said notches 32, are made long enough to permit the lock bolts or lugs 28, to be wholly withdrawn from the notches in the internal lock members 26, as clearly 35 illustrated in Fig. 2, where it will be seen that said notches 32, are in position registering with the ends of the internal lock members 26. In operation, the external locking mechanism is unlocked and the hasp member swung into the position, indicated 40 in dotted lines in Figs. 2, and 3, to unlock the internal locking mechanism; the lock bar is thereby raised out of locking engagement with the internal lock members, through the instrumentality of the 45 segmental rack. The two trunk sections may then be swung open. To lock the trunk the sections are swung together, and the hasp member is thereafter swung down into register with the external socket member, the 50 straight edge 22, of the segmental rack thereupon striking against the adjacent edge of the lock bar 21. The hasp member is then locked to the socket member as usual, thereby locking the two sections together at 55 a plurality of places on its interior. The trunk cannot be unlocked at said places without first unlocking the exterior locking mechanism.

In the modified form shown in Fig. 7, the hasp member 15^a is connected to the lock bar 21^a, by an eccentrically disposed pin 19^a, secured in one member and projecting through a slot in the side of the trunk section and engaging the other member. In this case the 65 pin or bolt 18^a, simply acts as the fulcrum or

pivotal connection between the hasp member and trunk section; the lock bar and internal lock members may be constructed substantially as in the preferred form.

More or less variation of the exact details of construction shown and described is possible without departing from the spirit of this invention. We desire therefore, not to limit ourselves to the exact forms shown and described but intend in the following 75 claims to point out all of the invention disclosed herein.

We claim as new and desire to secure by Letters Patent:

1. Locking mechanism for portable containers, having two relatively movable sections, comprising an internal lock member fixedly secured to the inside of one section and adapted to project into the interior of the other section, said lock member having a notch in one edge, a reciprocatory lock bar slidably mounted on the inside of the other section and having a notch in its edge for the reception of the notched end of the lock member, and having an integrally formed lock bolt at the end of said notch, adapted to enter the notch in the lock member and coacting with said internal lock member to lock together the two sections of said container, an external locking member pivotally mounted on the outside of the section containing the lock bar, and operatively connected with said lock bar, and a socket member mounted on the outside of the other section and adapted for locking engagement with said external locking member.

2. Trunk locking mechanism comprising a plurality of internal lock members, fixedly secured to the inside of one section of a trunk and having bolt engaging portions, a reciprocatory lock bar slidably mounted on the inside of the other section and having lock bolts rigidly secured thereto and cooperating with said internal lock members to lock together the two trunk sections, said lock bar having also a toothed rack at one end, a hasp member pivotally mounted on the outside of the trunk section containing the lock bar, a segmental rack, fixedly secured to the hasp member, and meshing with said toothed rack of the lock bar, and a socket member secured to the outside of the other trunk section and adapted for locking engagement with said hasp member.

3. Trunk locking mechanism for securing together two sections of a trunk, comprising a plurality of internal lock members secured to the inside of one trunk section and having notched end portions extending into the other trunk section, a reciprocatory lock bar slidably mounted in said other trunk section and being formed with lugs, one for each lock member, said lugs having tapered edges adapted to be forced into said notches of the

end portions of the internal lock members with a wedge-like action, a hasp member pivotally mounted on the outside of the trunk section containing the lock bar, a 5 socket member engaged by said hasp member and secured on the other trunk section, and operative connections between said hasp member and lock bar for converting oscillatory movements of said hasp member into 10 reciprocating movements of said lock bar.

4. Trunk locking mechanism for securing together two sections of a trunk, comprising a plurality of internal lock members secured to one trunk section and having end portions 15 adapted to extend into the other trunk section, said end portions being formed with notches in their upper edges and upstanding

lugs beyond the notches, and each notch having an inclined edge slanting down from said lug, a reciprocatory lock bar slidably mounted in straps secured to said other trunk section, said lock bar being formed with lugs adapted to enter said notches in the internal lock members, and said lugs having inclined edges for engagement with the inclined edges of the notches, said lock bar being also formed with notches for the reception of the notched ends of the internal lock members, and means for reciprocating said lock bar including the hasp member of 20 25 an external locking mechanism.

GEORGE F. GRUBE.
JULIUS V. MEYERING.
